CLAIM

We claim the ornamental design for a center display screen with controls for automotive vehicle, as shown and described.

DESCRIPTION

FIG. 1 is a perspective view of a center display screen with controls for automotive vehicle, of the new design;
FIG. 2 is an enlarged front-perspective view thereof;
FIG. 3 is a back-perspective view thereof;
FIG. 4 is a front view thereof;
FIG. 5 is a top view thereof;
FIG. 6 is a side view thereof;
FIG. 7 is a side view thereof, opposite that of FIG. 6;
FIG. 8 is a bottom view thereof; and,
FIG. 9 is a back view thereof.

In the drawings, the broken lines depict portions of the center display screen with controls for the automotive vehicle, that form no part of the claimed design. The vehicle dashboard shown in broken lines is for environmental subject matter only and forms no part of the claimed design.
